SPINNING FRAME DRUM SPREADER

Saint Julian Geddings, West Columbia, S. C.

Application January 8, 1941, Serial No. 373,684

16 Claims.

(Cl. 254—29)

My invention is a device for separating the adjacent ends of the drums of a spinning frame, twister frame, or like textile machinery, so that the arbor or shaft supporting the drums may be removed.

In the ordinary spinning frame, there are a number of drums arranged in end-to-end relation. A narrow belt is passed about each drum and drives a set of four spindles. These drums have a periphery formed of thin light sheet metal and the periphery must be true as the drums are driven at a speed of about 1200 R. P. M. and if the periphery is not true, the machine will vibrate and otherwise operate unsatisfactory. It is the practice to mount a pair of heads or ends of the adjacent drums upon a short shaft or arbor, journaled in a ball-bearing. The heads or ends are recessed and the ball-bearing projects into these recesses and it is impossible to remove the bearings without separating the drums. It is also impossible to remove the short shaft or arbor without separating the drums. The pair of heads or ends of the adjacent drums are arranged in close relation and are spaced for about seven-eighths of an inch. This small space between the heads or ends has rendered it difficult to spread or separate these heads or ends and the same has been done, as far as I am aware, by prying the heads or ends apart by inserting a crowbar or like tool between the same. The operation is therefore manual. It frequently happens that in spreading or separating the heads or ends in this manner the periphery of the drum is warped or bent, due to the thin gauge of the metal forming the same with the result that the drum is frequently ruined. Further, the head or end which is ordinarily made of cast iron is frequently broken. Due to the small space between these heads or ends, as far as I am aware, no device has been produced which will operate within this narrow space, to properly spread the heads or ends without injury to the heads or ends or the periphery of the drum. A similar situation exists with respect to the drums of twister frames.

An important object of my invention is to provide a device having parts which are inserted in the narrow space between the heads or ends, and will spread or separate the same, and exert pressure upon the heads or ends in a proper manner, so that the heads or ends will not be broken or the periphery of the drum bent or injured.

A further object of the invention is to provide a device of the above-mentioned character having means to apply pressure upon the heads or drums at suitable points so that there will be no tendency

to twist or turn the heads or drums upon the short shaft or arbor.

A further object of the invention is to provide a device of the above-mentioned character which 5 may be applied to the adjacent end of one drum, upon the removal of the traverse rail of the spinning frame, and the device thus applied to the end of the drum will not bend or injure the periphery of the drum, while the operating parts project into the narrow space between the heads of the drums.

A further object of the invention is to provide a device of the above-mentioned character which is relatively simple in construction and powerful 15 in operation.

A further object of the invention is to provide hydraulic apparatus of the above-mentioned character, thereby producing a highly simplified construction.

20 A further object of the invention is to provide hydraulic apparatus of the above-mentioned character, all parts of which are portable.

A further object of the invention is to provide 25 a pump for supplying the fluid under pressure, such pump having means to mount the same upon the rail or rails of the spinning frame.

A further object of the invention is to provide 30 apparatus of the above-mentioned character which may be operated by a single operator.

Other objects and advantages of the invention 35 will be apparent during the course of the following description.

The present application is a continuation in part of my co-pending application for Spinning 35 frame drum spreader, filed April 4, 1940, Serial No. 327,869.

In the accompanying drawings forming a part 40 of this application and in which like numerals are employed to designate like parts throughout the same,

Figure 1 is a perspective view of a device embodying my invention,

Figure 2 is a transverse vertical section taken on line 2—2 of Figure 3,

45 Figure 3 is a vertical longitudinal section taken on line 3—3 of Figure 2,

Figure 4 is a front elevation of the device,

Figure 5 is an exploded perspective view of the upper feed screw and associated elements,

Figure 6 is a fragmentary edge elevation of the body portion,

Figure 7 is a transverse section taken on line 7—7 of Figure 2,

50 Figure 8 is a perspective view of apparatus embodying a second form of the invention,

Figure 9 is a central longitudinal section through one of the cylinders and associated elements, showing the device in place.

Figure 10 is a side elevation of a connecting strap, associated elements being shown in elevation and broken away.

Figure 11 is a central longitudinal vertical section through the pump.

Figure 12 is a transverse section taken on line 12-12 of Figure 11.

Figure 13 is a rear perspective view of the body portion of the apparatus and associated elements, and,

Figure 14 is a detailed section through the pressure equalizing coupling taken on line 14-14 of Figure 8.

In the drawings, wherein for the purpose of illustration are shown preferred embodiments of my invention, attention being called first to Figures 1 to 7 inclusive, the numeral 10 designates a body portion or frame, which is circularly curved. This body portion comprises a vertical web or plate 11, having an inner horizontal flange 12. The numeral 13 designates an adjustable vertical web having an inner horizontal flange 14. The web 13 forms in effect a continuation of the web 11 and the flange 14 a continuation of the web 12. When the web 13 is in the closed position, the webs 11 and 13 extend for considerably more than 180°. The web 13 is pivotally connected with the web 11, in a manner to be described. The body portion further comprises a vertical web or plate 15, arranged opposite the web 11 and spaced therefrom. The web 15 is co-extensive in length with the web 11. The numeral 16 designates an adjustable vertical web or plate, disposed opposite the web 13 and spaced therefrom, and the web 16 is co-extensive in length with the web 13. The web 16 is pivotally connected with the web 15, by means to be described.

The web 13, Figure 6, has an inwardly off-set knuckle 17, disposed inwardly of the web 11 and the web 16 has an inwardly off-set knuckle 18 disposed inwardly of the web 15. The webs 11 and 15 are rigidly connected by stub-shafts 19, Figure 7, having shoulders 20 and reduced screw-threaded ends 21, receiving nuts 22. The stub-shafts are therefore clamped to the webs 11 and 15. The upper stub-shafts 19 have their reduced ends 21 cut off and spread, so that they are flush with the surface of the web 15. The stub-shafts may be attached to the webs 11 and 15 by any suitable means. In a similar manner, the webs 13 and 16 are rigidly connected by means of stub-shafts 23, identical with the stub-shafts 19. The lowermost stub-shaft 19 has its reduced end cut off and spread and is arranged flush with the surface of the web 15 and the lowermost stub-shaft 23 has its reduced end cut off to spread and is arranged flush with the face of the web 16. Rotatably mounted upon the stub-shafts 19 and 23 are gears 24, having hubs 25, Figure 7. These gears are free to rotate and they form two groups of gears, the gears in each group being in permanent mesh. These gears 24 are identical in shape and size. One stub-shaft 19 has its ends inwardly of the shoulders 20 extending through the knuckles 17 and 18 and pivotally connects the web 13 with the web 11 and the web 16 with the web 15. When the webs 13 and 16 are swung upon the stub-shaft 19 as a pivot, the gear 24 of these webs travels about the adjacent gear 24 carried by the webs 11 and 15.

The numeral 26 designates an upper feed screw, having a flange 27 preferably integral therewith and a smooth portion 28. This smooth portion is rotatable within openings 29 and 30, formed in the webs 11 and 15. An end-thrust ball-bearing 31 is arranged between the flange 27 and the web 15. The numeral 32 designates a gear having a spacing hub 33. This gear is mounted upon the smooth portion 28 of the feed screw and is rigidly secured thereto to turn therewith by any suitable means such as a key, set-screws, or both. The gear 32 is preferably slightly larger than the gears 24 and is in mesh with the adjacent pair of gears 24, to turn therewith. Mounted upon the feed screw 26 and having screw-threaded engagement therewith is a sleeve 34, provided at its inner end with a horizontal arm or extension 35, carrying a radial jaw 36. The numeral 37 designates lower feed screws, similar to the feed screw 26 and mounted in a similar manner in openings formed in the lower ends of the webs 11 and 15 and the webs 13 and 16. The same flange 27 is provided for these feed screws and the same end-thrust ball-bearings. Gears 38 are rigidly mounted upon the smooth portions of the feed screws 37 and these gears are identical with the gear 32 and have the same spacing hubs. The gears 38 are in mesh with the adjacent gears 24 and are of the same shape and size as the gear 32. Sleeves 39 are mounted upon the feed screws 37 and have slideable engagement therewith and these sleeves have horizontal arms 40, corresponding to arm 35 and inwardly facing radial jaws 41, corresponding to the jaw 36. As clearly shown in Figure 4, the feed screws 26 and 37 are equidistantly spaced throughout 360° whereby the jaws will so distribute the pressure upon the head of the drum that there will be no tendency for the head to bend or buckle. While it is preferred to use three feed screws, yet I contemplate using a different number and may use two or any number over one, provided they are equidistantly spaced around 360°. The top screw 26 has right threads and the lower screws 37 have left threads and the action of the gears is such that these screws simultaneously move their sleeves outwardly at the same speed.

Power operated means is preferably provided to drive the gear 32. This means comprises a gear 42, engaging the gear 32 and rigidly mounted upon a shaft 43, rotatable within openings formed in ears or knuckles 44 and 45, integral with the webs 15 and 11. The shaft 43 extends outwardly beyond the knuckle 45 and has a worm wheel 46 rigidly secured thereto, held within a housing 47. This worm wheel is driven by a work 48, carried by a shaft 49, journaled in the ends of the lower portion 50 of the housing. The shaft 49 has a coupling 51, for connection with a shaft from a suitable source of power.

In Figure 3, I have shown the adjacent ends of a pair of drums 52. These drums have peripheries 53, in each end of which is rigidly mounted a head 54, having a hub 55. The hubs 55 are clamped to short shaft or arbor 56, held in a ball-bearing 57, carried by a portion 58 of the frame. The heads 54 have exterior recesses to receive the ball-bearing 57. The heads have peripheries 59 to which the drum periphery 52 is originally secured. The peripheries 59 have radial flanges 60. The space between the flanges 60 is narrow and is ordinarily seven-eighths of an inch.

The inner edge of the webs 15 and 16 extend

inwardly radially beyond the horizontal webs 12 and 14 providing a flange extending inwardly for substantially the same distance as the lugs 36 and 41.

The operation of the device is as follows:

To apply the device to the adjacent ends of the drums 52, the traverse rail is removed for affording access to the drums. The body portion or frame of the device is opened by swinging the webs 13 and 16 outwardly. The horizontal flanges 12 and 14 are applied to one drum directly over the periphery 59 of the adjacent head. These flanges are preferably of substantially the same width as the periphery 59 of the head 54, and hence the weight of the device is taken from the periphery 53 of the drum, which is thin and could be readily bent. The horizontal portion 50 of the housing is spaced from the periphery 53 and therefore cannot contact with it. The webs 13 and 16 are now swung to the inner or closed position. The inner edge of the webs 15 and 16 and the lugs 36 and 41 now substantially contact and their combined width is slightly less than seven-eighths of an inch so that they will enter the narrow space between the flanges 60. The inner edges of the flanges 15 and 16 engage the flange 60 of one drum while the lugs 36 and 41 engage the flange 60 of the other drum. The outer side of the flange 60 is that side which is remote from the space between the flanges 60. The shaft 43 is now rotated and this motion is transmitted by the gears to the feed screws. The jaws 36 and 41 are now moved from the webs 15 and 16, and the coacting webs and jaws spread the flanges 60 and their heads. Prior to this operation the set-screw of one hub 55 is loosened, such as the set-screw with the hub 55 to the left, while the other hub 53 remains clamped to the arbor 56. The head 54 to the left is therefore slid from the arbor 56. A similar head not having the drum attached thereto is now clamped to the left end of the arbor and the lugs are returned to the inner position. The set screw of the drum 54 to the right is now loosened and the device is operated to again shift the lugs 36 to the left. This withdraws the arbor from the hub of the head 54 to the right. I have found that by the use of my device, the heads may be separated or spread and that they will not be broken nor will the peripheries 53 of the drums be bent or injured.

In Figures 8 to 14 inclusive, I have shown a modification of the invention embodying hydraulic apparatus. This apparatus comprises a body portion or frame 61 which is circularly curved. This body portion comprises vertical webs or plates 62. One vertical web 62 is provided with a laterally off-set knuckle 63, arranged upon one side of the companion web or plate 62 and pivotally connected therewith by means of a bolt 64 or the like. The frame 61, including the assembled vertical webs or plates 62, extends for more than 180°. The vertical webs 62 are provided with horizontal flanges 65, the upper ends of which substantially contact when the body portion is closed but are free from connection. The body portion may be opened by swinging the vertical webs or plates 62 about the pivot 64. The horizontal flange 65 of each vertical web 62 is preferably formed integral therewith, forming a raised portion 66 having a groove 67 providing a shoulder 68 which is the end wall of the horizontal flange 65. This arrangement spaces the end wall 68 from the vertical web 62, as shown. At its free or lower end, one horizontal flange 65 carries a

hook 69, preferably formed integral therewith and this hook is received within the opening 70 of a strap 71, secured to a liner 72. The opposite end of the strap is in the form of a screw-threaded rod 73, to be arranged between spaced lugs 74, formed integral with the lower or free end of the companion horizontal flange 65. The screw-threaded rod carries a nut 75 and washer 76, as shown. The purpose of this strap is to retain the frame sections in the closed position when applied to the work, but I found that the apparatus may be used without this strap, as there is little tendency for the frame sections to open in use.

Preferably formed integral with the vertical webs or plates 62 of the frame sections are horizontal cylinders 77, which are spaced for 180°. This is the arrangement when two of these cylinders are used but the number may be increased and where more than two are used the cylinders 20 will be equidistantly spaced. The cylinders receive reciprocating plungers 78, carrying plunger rods 79, operating through tubular caps 80, having screw-threaded engagement with the cylinders. Each plunger 78 is provided with suitable packing 81 and a compressible coil spring 81' surrounds the plunger rod 79 and is confined between the plunger 78 and the tubular cap 80. Each plunger rod 79 projects beyond the tubular cap and is provided with a reduced cylindrical portion 82 upon which is rotatably mounted a sleeve 83, engaging against a shoulder 84 and held in place by a nut 86. The sleeve carries a lateral extension 87 having a radial jaw or spreading element 88.

35 Formed integral with one vertical web 62, upon one side of the bolt or pivot 64, is a tubular boss 89, for receiving a trunnion 90, which is clamped within the tubular boss by a set screw 91. The boss 89 is formed integral with a pressure distributing or equalizing coupling 92. A pipe 93 engages within a screw-threaded opening formed in the coupling 92 and has communication with the interior thereof and this pipe leads to a coupling 94, discharging into the inner or closed end of one cylinder 77. A flexible pipe or hose 95 also leads into the coupling 92 through the medium of a coupling 96 and this flexible pipe is connected with a rigid pipe 97 which leads into the inner or closed end of the other cylinder 77 through the medium of a coupling 98. The coupling 92 is preferably formed integral with a cut-off valve 99 having an inlet tubular portion 100.

The numeral 101 designates a flexible hose, equipped with a cut-off valve 102 having a tubular outlet portion 103 and carrying a coupling 104 for detachably connecting the valves 102 and 99.

Means are provided to supply a liquid, such as oil, under pressure through the hose 101, including a manually operated pump. This pump 60 comprises a vertical cylinder 105, mounted upon a base 106 also carrying a vertical reservoir or tank 107. The tank 107 has a port 108 leading into its bottom and this port leads into a vertical port 109 discharging into the bottom of the cylinder 105. There is a valve seat 110 engaged by a downwardly closing ball check valve 111 within a cage 112. A plunger 113 reciprocates within the cylinder 105 and is provided with suitable packing and this plunger extends above the cylinder 105 and is pivotally connected at 114 with a vertically swinging lever 115, pivoted at 116 with a link 117, which is pivotally supported at its lower end at 118. The cylinder 105 has a horizontal port 119 arranged at a right angle to

the port 108 and this port 119 leads into a vertical port 120 having a seat 121 for an upwardly opening ball check valve 123. A vertical pipe 124 leads into the vertical port 121 and this pipe 124 has a T-coupling 125, one end of which is connected with the flexible hose 101. The T-coupling 125 is connected with a branch return pipe 126 having a cut-off valve 127 and this return pipe 126 leads into a port 128, in communication with the port 108.

The tank 107 is provided with a vertical bracket 129, rigidly secured thereto, and this bracket carries horizontal clamps 130, to engage over the spindle rails 131 of a spinning frame. These clamps carry set screws 132, as shown.

The operation of this form of the apparatus is as follows:

The valve 99 is now closed so that the oil cannot discharge from the cylinders 77 and the valve 102 is closed, and the valves 102 and 99 are now separated. The frame sections are shifted to the outer position and the frame or body portion is now brought into proximity to the adjacent ends of the drums 52, the traverse or ring rail being removed. The horizontal flanges 65 are now applied to one drum directly over the periphery 59 of the adjacent head 54. The horizontal flanges 65 are preferably of substantially the same width as the periphery 59 of the head 54, and hence the weight of the device is taken from the periphery 53 of the drum, which is thin and could be readily bent. The frame sections including the vertical webs 62 are now swung to the inner or closed position, the inner ends of the horizontal flanges 65 now substantially contacting. The inner edges of the vertical webs 62 pass between the flanges 60 of the heads 54 while one flange 60 projects into the groove 67 and is arranged to engage with the end wall 68 of the horizontal flange 65. The sleeves 87 have previously been turned so that the radial jaws 88 extend outwardly, and these sleeves are now turned around so that the jaws 88 also extend between the flanges 60. The combined thickness of the webs 62 and the jaws 88 is slightly less than seven-eighths of an inch so that they will enter the narrow space between the flanges 60. The vertical webs 62 engage one flange 60 while the jaws 88 engage the other flange 60. If desired, the strap 71 is applied to the lower ends of the frame sections to hold them against any possibility of opening.

The pump is now applied to the rails 131 suitably near the body portion 61. The coupling 104 is now employed to connect valves 102 and 99 and these valves are now both opened, while the valve 127 is closed. The lever or handle 115 is now reciprocated and when the plunger 113 is raised the oil enters the cylinder 105 through the port 108 and when the plunger 113 moves downwardly ball check valve 111 closes and the oil under pressure is forced through the port 119 past check valve 123 into the hose 101. When the plunger 113 rises check valve 123 closes. It is thus seen that by operating the pump the liquid or oil under pressure will be supplied to the inner ends of the cylinders 77, and the pressure in these cylinders will be equal. The plungers 78 move forwardly carrying the jaws 88 with them. The jaws therefore move the flange 60 to the left from the flange 60 to the right and the head 54 to the left is removed from the shaft 56, the set screw to the left being first unscrewed, while the hub 55 to the right remains clamped to the arbor 56. The head 54 to the left is there-

fore slid from the arbor 56. A similar head not having the drum attached thereto is now clamped to the left end of the arbor 56 and the plungers 78 are returned to the inner position, which is effected by stopping the pumping action and opening the valve 127, as will be more fully explained. The vertical webs 62 and the jaws 88 are now positioned between the pairs of flanges 60, the drum 54 to the left being now clamped to the arbor 56 while the set screw of the drum 54 to the right is unscrewed. The apparatus is then operated to move the plungers 78 outwardly and this withdraws the arbor 56 from the hub of the head 54 to the right. I have found that by the use of this device, the heads may be separated or spread and that they will not be broken nor will their peripheries 53 be bent or injured. When this operation is completed, valves 102 and 99 remaining open, valve 127 is opened and the pressure is returned through the hose 101 and passes through return pipe 126 through port 128 back into the reservoir or tank 107. After this operation valves 102 and 99 are both closed to prevent the escape or loss of the oil or the fluid subsequently to which these valves are separated by the manipulation of the coupling 104. The valve 127 may now be closed, if desired. The pump may now be separated from the rails 131 and the frame 61 removed from the drum 52.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described my invention, what I claim is:

1. A device for spreading the spaced ends of drums of a spinning frame, twister frame or like textile machine, comprising a body portion to be arranged exteriorly of the drum and extending about the same for more than 180°, the body portion having an adjustable side, the body portion having a part projecting into the space between the ends of the heads of the drums, feed screws carried by the body portion and substantially equidistantly spaced, devices carried by the feed screws and having inwardly projecting jaws to enter said space and be arranged opposite said part, gears mounted upon the feed screws, gears mounted upon the body portion and engaging the gears of the feed screws so they turn in unison, and means to drive the gear carried by one feed screw.

2. A device for spreading the spaced ends of drums of a spinning frame, twister frame or like textile machine, comprising a curved body portion including a vertical web having a horizontal web at its inner edge, an opposed vertical web projecting inwardly beyond the horizontal web, shafts connecting the vertical webs, gears arranged between the vertical webs and mounted upon the shafts, feed screws mounted upon the body portion, gears carried by the feed screws and engaging certain of the first named gears, sleeves carried by the feed screws and having inwardly projecting jaws, and means to drive one of the gears.

3. A device for spreading the spaced ends of drums of a spinning frame, twister frame or like textile machine, said device comprising a body portion to be arranged upon the exterior of one drum adjacent to its end and extending circumferentially of the drum, a part carried by the

body portion and extending into the space between the ends of the drum to hold the body portion against movement from the end of the drum so that the body portion is retained at the selected position upon the drum, feed screws carried by the body portion and extending longitudinally of the drums, sleeves carried by the feed screws and having jaws extending into the space between the ends of the drums and serving to move one drum from the other drum, and means to turn the feed screws.

4. A device for spreading the spaced ends of drums of a spinning frame, twister frame or like textile machine, said device comprising an elongated body portion to be arranged upon the exterior of one drum adjacent to its end and extending circumferentially of the drum, said body portion having a relatively stationary part projecting into the space and engaging the end of the drum to hold the body portion against movement from such end so that the body portion is retained at the selected position upon the drum, feed screws carried by the body portion and extending longitudinally of the other drum, sleeves mounted upon the feed screws and having jaws extending into the space between the ends of the drums and arranged between said relatively stationary part and the end of the other drum, and means mounted upon the body portion to turn the feed screws so that the jaws move longitudinally of the other drum from the relatively stationary part.

5. Apparatus for spreading the spaced ends of drums of a spinning frame, twister frame or like textile machine, said drums having a thin periphery and heads at their ends, said apparatus comprising a body portion having a curved recess to receive the periphery of one drum and extending circumferentially thereof, said body portion including a web to engage with that portion of the drum periphery which is directly supported by the head, a vertical web spaced from and connected with the first named web and extending radially inwardly beyond the same and engaging with the end of the drum, the vertical web holding the body portion against movement from the end of the drum so that the first named web is retained upon that portion of the periphery of the drum which is directly supported by the head, feed screws mounted upon the body portion and extending longitudinally of the other drum, sleeves mounted upon the feed screws and having inwardly extending jaws, said jaws being arranged between the ends of the drums with the vertical web, and means mounted upon the body portion to rotate the feed screws.

6. A device for spreading the spaced ends of drums of a spinning frame, twister frame or like textile machine, said device comprising a body portion to be arranged exteriorly of one drum and having a recess to receive the periphery of said drum, said body portion extending circumferentially of the periphery, a train of gears mounted upon the body portion, means for affecting a spreading movement between the ends of the drums including screw-threaded elements driven by certain of the gears of the train, and means to drive one of the gears of the train.

7. A device for spreading the spaced ends of drums of a spinning frame, twister frame or like textile machine, said body portion to be arranged exteriorly of one drum, cylinders secured to the body portion, plungers operating within the cylinders and having plunger rods, spreading elements carried by the plunger rods and arranged for insertion between the spaced ends of the drums,

means carried by the body portion and stationary with relation thereto and to be arranged between the spaced ends of the drums to engage the end of the drum carrying the body portion to hold the body portion against movement in one direction, and means to supply a fluid under pressure into the cylinders.

8. A device for spreading the spaced ends of drums of a spinning frame, twister frame or like textile machine, said device comprising a body portion to be arranged exteriorly upon one drum and having an inwardly extending part which is relatively stationary with respect to the body portion and to be arranged between the ends of the drums to bear against the end of the drum which carries the body portion, plungers operating within the cylinders and having plunger rods, spreading elements carried by the plunger rods and arranged for insertion between the inwardly extending part and the end of the other drum to bear against such end, and means to supply fluid under pressure into the cylinders.

9. A device for spreading the spaced ends of drums of a spinning frame, twister frame or like textile machine, said drums having a thin periphery and heads at their ends, said heads having radial flanges extending beyond the peripheries of the drums, said apparatus being adapted to be arranged upon the periphery of one drum adjacent to its head, said body portion being provided with a recess to receive one flange and having an inwardly projecting part to be arranged between the flanges, cylinders mounted upon the body portion, plungers within the cylinders and having plunger rods, spreading elements carried by the plunger rods and arranged to be disposed between the flanges, and means to supply a fluid under pressure into the cylinders.

10. A device for spreading the spaced ends of drums of a spinning frame, twister frame or like textile machine, said drums having flanges adjacent to their ends, said device comprising a body portion to be arranged upon one drum adjacent to the flange and having a recess to receive the flange and also having an inwardly projecting part to be arranged between the flanges, cylinders mounted upon the body portion, plungers within the cylinders having plunger rods, springs to move the plungers in one direction, means to supply fluid under pressure into the cylinders, and spreading elements pivotally mounted upon the plunger rods and having parts to be arranged between the flanges of the drums.

11. A device for spreading the spaced ends of drums of a spinning frame, twister frame or like textile machine, said device comprising a body portion having a recess to receive the periphery of one drum, said body portion including sections which are hinged together, each section comprising a radial web to extend into the space between the drums and a flange to rest upon the drum, cylinders carried by the sections, plungers within the cylinders having plunger rods, spreading elements carried by the plunger rods and adapted to be arranged within the space between the drums, and means to supply fluid under pressure into the cylinder.

12. A device for spreading the spaced ends of drums of a spinning frame, twister frame or like textile machine, said device comprising a body portion having a recess to receive the periphery of one drum, said body portion including sections which are hinged together,

each section comprising a radial web to extend into the space between the drums and a flange to rest upon the drum, cylinders carried by the sections near their free ends, an equalizing coupling mounted upon one section, means connecting the equalizing coupling with the cylinder carried by its section, means including a flexible hose connecting the coupling with the cylinder of the other section, and means to supply a fluid under pressure into the coupling.

13. A device for spreading the spaced ends of drums of a spinning frame, twister frame or like textile machine, said device comprising a body portion having a recess to receive the periphery of one drum, said body portion comprising sections which are hinged together, each section comprising a radial web to extend into the space between the drums and a flange to rest upon one drum, horizontal cylinders rigidly secured to the sections near their free ends and extending longitudinally of the drum, an equalizing coupling connected with the cylinders, plungers within the cylinders having plunger rods, spreading elements carried by the plunger rods and adapted to be arranged between the drums, and means to supply a fluid under pressure into the coupling.

14. A device for spreading the spaced ends of drums of a spinning frame, twister frame or like textile machine, said device comprising a body portion having a recess to receive the periphery of one drum, said body portion including a radial web to extend into the space between the drums and a flange to rest upon the drum, cylinders carried by the body portion, a cut-off valve connected with the cylinders, a hose having a coupling for detachable connection with the cut-off valve, a cut-off valve connected in the hose, a liquid pump having an outlet connected with the hose, a by-pass pipe connected with the hose and leading into the pump, a cut-off valve in the by-pass pipe, and means carrying the pump and having means to clamp the same to spindle rails, and spreading elements connected with the plungers within the cylinders.

15. Apparatus for spreading the spaced ends of drums of a spinning frame, twister frame or like textile machine, said drums having thin peripheries and heads at their ends, said heads having radial flanges extending beyond the peripheries, said apparatus comprising a body portion to extend circumferentially of the periphery of one drum and to be arranged upon such periphery adjacent to and upon the outer side of the flange of such drum and engaging that portion of the periphery which is directly over and supported by said head, a relatively stationary element secured to the body portion and adapted to extend into the space between the ends of the drums upon the inner side of the flange of the first drum to contact with the head of the first drum and to hold the body portion against outward movement in position substantially directly over the head of the first drum, spreading means mounted upon the body portion and extending into the space between the inner sides of the flanges and disposed between the relatively stationary element and the inner side of the flange of the other drum, and means to move the spreading means from the element.

16. A device for spreading the spaced ends of drums of a spinning frame, twister frame or like textile frame, said device comprising a body portion to be arranged upon the exterior of one drum, means secured to the body portion and extending into the space between the ends of the drums and engaging the end of the drum which carries the body portion and serving to prevent relative movement between the body portion and the drum carrying it during the spreading operation, spreading means mounted upon the body portion and extending into the space between the ends of the drums for engaging the drum remote from the body portion, and means to operate the spreading means to effect a relative spreading action between the drums.
